UNITED STATES PATENT OFFICE.

SYLVESTER M. SCHWELLER, OF DAYTON, OHIO, ASSIGNOR TO DELCO-LIGHT COMPANY,
OF DAYTON, OHIO, A CORPORATION OF DELAWARE.

REFRIGERATING APPARATUS.

Application filed November 26, 1923. Serial No. 677,138.

The present invention relates to refrigerators and has for one of its objects the provision of a cover plate within one of the compartments of the refrigerator for covering the mechanism therein, the construction being such that the cover is readily removable whereby access may be had to the interior of the compartment.

Further objects and advantages of the present invention will be apparent from the following description, reference being had to the accompanying drawings, wherein a preferred form of embodiment of the present invention is clearly shown.

15 In the drawings:

Fig. 1 is a front elevational view of a refrigerator, one of the doors thereof being swung to open position.

Fig. 2 is a sectional view taken on line 20 2-2 of Fig. 1.

Fig. 3 is a sectional view taken on line 3-3 of Fig. 2.

Fig. 4 is a fragmentary sectional view taken on line 4-4 of Fig. 2.

25 Referring to the drawings, 20 is a refrigerator including a food storage compartment 21 and a cooling compartment 22. Compartments 21 and 22 are provided with doors 23 and 24 respectively, and with linings 25 and 26 respectively. The compartments are insulated from one another by cork 27. Cold air from the cooling compartment 22 passes through a flue 28 into the food compartment 21 and the relatively 30 warm air passes from the food compartment 21 through a flue 29.

A cooling unit 30 comprising an evaporator for a mechanical refrigerating system and including a header 31 and pipes 32 is 40 carried within the cooling compartment 22. The support for said unit 30 includes straps 33 fitted about the header and which are connected by bolts 34 with a cross bar 35 carried by the cabinet 20. Ice tray sleeves 45 36 forming freezing chambers are carried by the pipes 32 by straps 37. Sleeves 36 slidably carry trays 38 in which water is placed to be frozen. Finished fronts 39 and handles 40 are provided for the trays 38.

50 The upper end of the front frame 42 of the refrigerator is cut away to form a recess 43 between the same and an outwardly extending flange of the lining 26. Recess 43 is adapted to receive the upper end of a finished front cover plate 45. Cover plate

45 is interposed between the door opening and the cooling unit 30 and is bent inwardly adjacent the ice trays 38 and is provided with openings 46 through which the trays can pass. The plate 45 is carried by spacers 48 at its lower end and which are suitably secured to the lining 26. Spacers 48 are provided with feet 49 soldered to lining 26 and with a relatively long portion 50 upon which the plate 45 rests and which can be readily bent upwardly or downward whereby the holes 46 in the plate 45 can be aligned with respect to the sleeves 36. The sides of the plate 45 about the lining 26 and the lower end of the plate are held against 55 the lining 26 by ears 51 formed integral with spacers 48 and which can be bent for holding said lining firmly in position.

The spacers 48 hold the plate 45 off of the lining 26 and thereby form a passage 52 between the plate and lining through which water, which condenses on the door and the front of the plate 45 and drips upon the door sill and lining, may pass into compartment 22 whence it is drained in any 60 well known manner.

The width of the plate 45 is less than the width of the door opening whereby the plate can be removed therethrough. It is only necessary to lift the plate 45 high 65 enough so that the lower end clears the ear 51 and then by pulling outwardly it can be removed.

In the present invention the cooling unit 30 is located at one side within the compartment 22 while the other side is utilized as a storage compartment 53 where articles can be placed which are desired to be kept relatively cool. An opening 54 is provided in plate 45 through which access may be had 70 to the interior of compartment 53.

It is apparent from foregoing that there has been provided a refrigerator having a cooling compartment having a relatively large door therefore but in which the entire cooling compartment is not subjected to the surrounding temperature when the door is opened and in which ready access may be had to the interior of the entire compartment. The plate 45 covers a substantial part of the cooling compartment, there being openings for the access to compartment 53 and to trays 38, and this plate is readily removable whereby access may be readily had to the cooling unit.

The openings 46 in the plate 45 can be aligned with the sleeve 36 in a very easy manner and the water which condenses on the door and on the front of plate 45 is directed into the compartment 22. The portion 50 of the spacer 48 can be raised very easily whereby the alignment may be had. This portion can be readily bent with any suitable tool such as a screw driver. While at the same time the spacers function to hold the plate off of the lining to form a passage 52 underneath the plate.

While the form of embodiment of the invention as herein disclosed, constitute a preferred form, it is to be understood that other forms might be adopted, all coming within the scope of the claims which follow.

What is claimed is as follows:

1. In a refrigerator, a compartment having an opening and a door therefor, a cooling unit located within said compartment, said compartment including a wall having a recess, and a cover plate for the cooling unit having a portion extending into said recess for removably holding the cover between the door and cooling unit.

2. In a refrigerator, a compartment having an opening and a door therefor, said compartment including a bottom wall, a cooling unit located within said compartment, a cover plate extending across the opening aforesaid and interposed between the door and said unit and carried by the wall, the lower edge of said plate being spaced from the wall for the purpose described.

3. In a refrigerator, a compartment having an opening and a door therefor, said compartment including a bottom wall and a cooling unit located within said compartment and comprising a freezing chamber, a removable cover plate extending across the opening aforesaid and interposed between the door and cooling unit and having an opening adjacent said freezing chamber, and means for holding said plate with its lower edge in spaced relation with said bottom wall and for aligning the opening in the plate with the chamber.

In testimony whereof I hereto affix my signature.

SYLVESTER M. SCHWELLER.
